(57) **CLAIM**

The ornamental design for a magnetic bead separation rack, as shown and described.

DESCRIPTION

FIG. 1 is a front perspective view of a first embodiment of the magnetic bead separation rack;

FIG. 2 is a side elevational view of the magnetic bead separation rack of FIG. 1;

FIG. 3 is a top elevational view of the magnetic bead separation rack of FIG. 1;

FIG. 4 is a bottom elevational view of the magnetic bead separation rack of FIG. 1;

FIG. 5 is a front elevational view of the magnetic bead separation rack of FIG. 1;

FIG. 6 is a back elevational view of the magnetic bead separation rack of FIG. 1;

FIG. 7 is a front perspective view of a second embodiment of the magnetic bead separation rack;

FIG. 8 is a side elevational view of the magnetic bead separation rack of FIG. 7;

FIG. 9 is a top elevational view of the magnetic bead separation rack of FIG. 7;

FIG. 10 is a bottom elevational view of the magnetic bead separation rack of FIG. 7;

FIG. 11 is a front elevational view of the magnetic bead separation rack of FIG. 7; and,

FIG. 12 is a back elevational view of the magnetic bead separation rack of FIG. 7.
